[57] **CLAIM**

The ornamental design for a cocktail table, substantially as shown and described.

DESCRIPTION

FIG. 1 is a front perspective view of a cocktail table embodying my new design;
FIG. 2 is a side elevational view thereof;
FIG. 3 is a top plan view thereof;
FIG. 4 is a front elevational view thereof;
FIG. 5 is a rear elevational view thereof;
FIG. 6 is front perspective view of a second embodiment of the cocktail table of my new design;
FIG. 7 is a side elevational view of the cocktail table of FIG. 6;
FIG. 8 is a top plan view of the cocktail table of FIG. 6;
FIG. 9 is a front elevational view of the cocktail table of FIG. 6; and
FIG. 10 is a rear elevational view of the cocktail table of FIG. 6.
The sides of the table forms not shown are mirror images of the sides shown in FIGS. 2 and 7 respectively.
